CLAIM

The ornamental design for a rail vehicle, as shown and described.

DESCRIPTION

This application contains subject matter related to the following co-pending U.S. design patent application:
Application Ser. No. 29/621,467, filed Oct. 9, 2017 and entitled "Rail Vehicle."

FIG. 1 is a front, top and left side perspective view of a rail vehicle according to the design;

FIG. 2 is a front elevational view thereof;

FIG. 3 is a rear elevational view thereof;

FIG. 4 is a left side elevational view thereof;

(Continued)

FIG. 5 is a right side elevational view thereof;
 FIG. 6 is a top plan view thereof;
 FIG. 7 is a bottom plan view thereof;
 FIG. 8 is an enlarged cross-sectional view thereof taken along line 8-8 of FIG. 2;
 FIG. 9 is an enlarged cross-sectional view thereof taken along line 9-9 of FIG. 2;
 FIG. 10 is an enlarged cross-sectional view thereof taken along line 10-10 of FIG. 2;
 FIG. 11 is a partial enlarged view illustrating box 11 of FIG. 1; and,
 FIG. 12 is an enlarged view of FIG. 4.
 The dotted broken lines illustrate unclaimed features of the rail vehicle. The dot-dash broken lines illustrate enlarged portions of the rail vehicle. The broken lines form no part of the claimed design.

1 Claim, 6 Drawing Sheets
